PENCIL SHARPENER

Edward C. Hoffmann, University City, Mo., assignor to Triple "E" Products Co., St. Louis, Mo., a corporation of Missouri

Application December 28, 1939, Serial No. 311,261

6 Claims. (Cl. 120—96)

The present invention relates generally to sharpeners, and more particularly to a motor-driven pencil sharpener automatically placed in motion by the pencil being inserted for sharpening.

An object of the present invention is to provide a novel power-driven pencil sharpener.

Another object is to provide a power-operated pencil sharpener which is automatically set in motion by the pencil being inserted for sharpening.

Another object is to provide a motor-actuated pencil sharpener of a construction to prevent shavings, dust, and the like, from passing to the motor.

Another object is to provide a motor-operated pencil sharpener, the connections between the sharpener and the motor of which are constructed to prevent stalling or jamming of the motor during the sharpening of a pencil.

Another object is to provide a power-driven pencil sharpener having means to receive pencils of different diameters.

Another object is to provide a power-actuated pencil sharpener in which the cutting mechanism is disposed at an angle to the horizontal of less than 90°.

Another object is to provide a motor-operated pencil sharpener having a high-speed small motor connected to the pencil-sharpening mechanism by indirect driving mechanism.

Another object is to provide a novel, compact, power-driven pencil sharpener sufficiently small to be used upon a desk or upon a wall.

Another object is to provide a compact, power-operated pencil sharpener, small enough for use upon a desk or wall, yet powered sufficiently to prevent stalling or jamming of the motor during sharpening of the pencil.

Another object is to provide a power-actuated pencil sharpener which is efficient in operation and which is adapted to fulfill all of the objects and advantages therefor.

Other objects and advantages will be apparent from the following description, taken in conjunction with the accompanying drawings, in which:

Fig. 1 is a front view of a power-actuated pencil sharpener constructed in accordance with the teachings of the present invention;

Fig. 2 is a central sectional view through the housing of the pencil sharpener shown in Fig. 1, the internal mechanism being shown in side elevation;

Fig. 3 is a section on the line 3—3 of Fig. 2;

Fig. 4 is a section on the line 4—4 of Fig. 1;

- Fig. 5 is a section on the line 5—5 of Fig. 4;
 Fig. 6 is a section on the line 6—6 of Fig. 2;
 Fig. 7 is a section on the line 7—7 of Fig. 4;
 Fig. 8 is a section on the line 7—7 of Fig. 4, the 5 mercury switch being shown in contact relation;
 Fig. 9 is a section on the line 9—9 of Fig. 4;
 Fig. 10 is a section on the line 10—10 of Figs. 3 and 11;
 Fig. 11 is a section on the line 11—11 of Fig. 3, 10 a pencil being shown in dotted lines with the point engaging the blunt-point stop;
 Fig. 12 is a section on the line 11—11 of Fig. 3, a pencil being shown in dotted lines with the point against the fine-point stop;
 15 Fig. 13 is a section on the line 13—13 of Figs. 4 and 11;
 Fig. 14 is a section on the line 14—14 of Figs. 3 and 11;
 Fig. 15 is a section on the line 15—15 of Figs. 3 and 11;
 20 Fig. 16 is an enlarged side view of the cutting mechanism with the cutter cylinders removed;
 Fig. 17 is an enlarged top view of elements of the cutter mechanism, showing a modified web; and,
 25 Fig. 18 is a section on the line 18—18 of Fig. 1.
 Referring to the drawings more particularly by reference numerals, there is disclosed a power-actuated pencil sharpener generally designated 20. A base or support 21 (Figs. 2 and 4) supports beneath a cover or casing 22 a motor 24, a cutter mechanism 25, a connecting drive mechanism 26, a switch mechanism 27, and a shavings drawer 28.
 30 The base 21 is preferably a casting comprising a horizontal portion 30, on the lower side of which is a rubber mat 29, a vertical fin 31, a wall 32 angularly disposed relative to the fin 31 and extending forwardly therefrom, a wall 33 disposed at right angles to the wall 32 and extending rearwardly from the fin 31, and a wall 34 (Figs. 2 and 3) which is connected to the edges of the wall 32 and the wall 33. A casting 36 is secured to the walls 32 and 34 by screws 37, and 35 includes a wall 38 parallel to the wall 33 and a wall 39 extending forwardly thereof of hood configuration. A plate 41, preferably of the configuration shown in Figs. 2-6, is secured to the free edge of the wall 39 by screws 42 and includes a flat portion 43 disposed in a plane parallel with the planes of the walls 33 and 36.
 40 The cover 22 is shown as of streamlined configuration. The cover 22 is secured to the horizontal portion 30 of the base 21 by pins 45 (Fig. 5) which extend into recesses 46 formed in the

forward corners of the horizontal portion 30, and by a screw 47 which extends through substantially the rearmost point of the horizontal portion 30 and into the wall of the cover 22. The configuration of the wall 34 conforms to the internal contour of the cover 22 in order to provide a snug fit therebetween to separate the space provided by the cover 22 into two compartments. A strip of felt, or the like (not shown), may be disposed between the exterior face of the wall 34 and the interior of the cover 22, if desired. The cover 22 includes a portion 49 which is in a plane parallel to the plane of the flat portion 43 of the plate 41 when the latter is operatively connected to the casting 36. The portion 49 has an aperture 50 to receive a pencil. The cover 22 further includes an opening 51 (Fig. 1) in the front end for the reception of the receptacle 28.

The motor 24 is secured by screws 52, or the like (Fig. 3), to the rear face of the wall 33. Power leads 53, 54, and 55 connect the motor 24 and the switch 27 in series, the leads 53 and 55 finding egress through the horizontal portion 30 of the base 21 (Fig. 2). The motor 24 includes a rotor shaft 57, one end of which extends through an aperture 58 in the wall 33.

The connecting drive mechanism 26 is disposed within a compartment formed by the wall 32, the wall 33, the wall 34, and the wall 38. The mechanism 26 includes a pinion 60 fixed by any suitable means to the rotor shaft 57 of the motor 24. Meshing with the pinion 60 is a gear 61 which is fixed to a shaft 62 rotatably mounted in suitable bearings bosses 63 and 64 formed integrally with the walls 33 and 38, respectively. A pinion 65 is also fixed to the shaft 62 to rotate with the gear 61. A gear 66 fixed to a reduced extremity 67 of a shaft 68 forming part of the cutter mechanism 25 meshes with the pinion 65.

The cutter mechanism 25 is disposed forwardly 40 of the wall 38 within the hood-shaped wall 39. The details of the cutter mechanism are clearly shown in Figs. 10-17. An annular member 70 is fixed to the forward face of the wall 38 by screws 71, or the like, and includes a central aperture 72 disposed in alignment with an aperture 73 formed in the wall 38. The member 70 further includes an inwardly disposed annular shoulder 74 and a ring gear 75. A portion of the annular member 70 is cut away to provide a slot 76 for a purpose to be discussed infra (Figs. 4, 11, and 13). The member 70 may be formed as an integral part of the casting 36.

The afore-mentioned shaft 68 of the cutter mechanism 25 is of the particular configuration shown in Figs. 11, 16, and 17. The shaft 68, in addition to the reduced extremity 67, includes a bearing segment 78 contiguous to the reduced extremity 67 and a bearing segment 79 at the opposite extremity thereof. The shaft 68 is formed to receive between the bearing segments 78 and 79 a pair of oppositely disposed cutter cylinders 80, each having affixed thereto at one end a gear-pinion 81. The cutters 80 and pinions 81 are rotatably mounted in the shaft 68 for free rotary movement relative thereto. The shaft 68 is, in effect, cut away to receive the cutter cylinders 80, leaving opposed webs 82 and 83. The web 82 is cut away at 84, through which extends an apron 85. The web 83 is cut away at 86, through which extends an apron 87. The aprons 85 and 87 are angularly disposed and converge at the axis of rotation of the shaft 68 to form a fine-point stop 88. An annular shoulder 90 is formed at the juncture of the 75

bearing segment 78 with the central portion of the shaft 68.

The bearing section 78 of the shaft 68 has bearing support in the aperture 72 of the annular member 70 with the annular shoulder 90 of the shaft 68 against the annular seat 74 of the annular member 70. The bearing segment 79 of the shaft 68 has bearing support in an aperture 91 formed in the portion 43 of the plate 41. The pinions 81 are in operative engagement with the ring gear 75.

A blunt-point stop 92 is mounted on the web 82 and includes a link 93 pivoted to a support 94 forming part of or secured to the web 82, 15 and a link 95 pivotally connected to the link 93. The link 95 extends through a suitable opening in the web 82 into the shaft 68. The blunt-point stop 92 is shown in Fig. 11 in operative disposition and in Fig. 12 in inoperative disposition.

A switch mechanism 27 is mounted on the hood-wall 39 (Figs. 4-8). A shaft 98 includes a first portion 99 journaled in a bearing 100 adjustably fixed by screws 101, or the like, to the outer face of the hood-wall 39, the bearing 100 including flanges 102 having slots 103 (Fig. 6) which receive the screws 101. The shaft 98 includes an intermediate portion 104 angularly disposed relative to the portion 99, and a third portion 105 which includes a flat face 106 angularly disposed relative to the plane of the portion 43 of the plate 41. A flat link 108 is fixed to the free end of the portion 99 of the shaft 98 by a nut 109, the link 108 bearing against a suitable shoulder formed near the end of the portion 99. A mercury switch 110 including a casing 111 having spaced wires 112 and a ball of mercury 113 therein is fixed to the other end of the link 108 by a clamp 114 which engages the casing 111 and which is secured to the link 108 by a nut 115. The switch mechanism 27 normally maintains the position shown in full lines in Fig. 5 through a stop 107 fixed to the shaft 98, but to close the circuit is easily rotatable to the position shown in the same figure in dotted lines. The leads 54 and 55 are connected to the spaced wires 112.

Pivoted on the portion 43 of the plate 41 below the aperture 91 is a size-plate 118 (Figs. 2-6 and 9). The plate 118 is fixed by welding or otherwise to a shaft 119 which has one reduced extremity 120 bearing in the portion 43 and a reduced portion 121 bearing in the portion 49 of the cover 22. A knob dial 122 is removably connected to a second reduced extremity 123 of the shaft 119 by a spring 124, or the like. The knob dial 122 has a pointer 125 (Fig. 1) which cooperates with indications 126 on the outer face of the portion 49 of the cover 22 to show the positions of size apertures 127 (Fig. 5) relative to the aperture 79. The plate 118 is disposed adjacent the outer face of the portion 43 of the plate 41.

In Fig. 17, webs 82' and 83' flare towards the end at which the aprons 85 and 87 are formed. Otherwise, the elements are the same as described. The flared construction assists in the direction of shaved material.

Operation

It is manifest that the pencil sharpener 20 just described is fully automatic in operation. It is flexible in that pencils of different sizes can be sharpened and a blunt or a fine point can be obtained.

Before sharpening a pencil, the size-plate 118 is adjusted by means of the knob indicator 122 to place the correct size opening in alignment with the aperture 79. The blunt-point stop 92 is adjusted to operative or inoperative position. Normally, the size-plate 118 will be disposed to receive a standard size pencil and the blunt-point stop 92 will be in inoperative position.

A pencil is thrust through the aperture 50. The point of the pencil contacts the face 106 of the shaft 98 and deflects the same to the right (Fig. 5), thereby rotating the switch mechanism 27 counterclockwise to move the casing 110 from the position shown in Fig. 7 to the position shown in Fig. 8, closing the motor circuit. The closing of the motor circuit and the starting thereby of the motor 24 and therefrom the cutter mechanism 25 through the drive mechanism 26 is substantially instantaneous so that the cutter cylinders 80 are in movement before the pencil comes into engagement therewith. The cutter cylinders 80 shave the graphite and encasing wood of the pencil until the point thereof contacts the fine-point stop 88, whereupon the cutter cylinders 80, although continuing to rotate, cease to actively point the pencil. This cessation of active shaving effect of the cutter cylinders 80 is immediately perceptible to the individual sharpening the pencil, so that the sharpened pencil can be withdrawn without loss of time.

The mechanical functioning of the pencil sharpener 20 is clear from the foregoing, taken in conjunction with the drawings. The motor 24 is of the high-speed type, a preferred motor running at 17,000 R. P. M. and adapted to function with either direct or alternate current. The drive mechanism 26 disposed between the motor 24 and the cutter mechanism 25 is an indirect drive, the advantages of which prevent stalling of the motor in sharpening a pencil. In a preferred embodiment, the high speed of the motor 24 is reduced by the connecting mechanism 26 to an effective speed of 500 R. P. M. as applied to the cutter mechanism 25. This ratio of 17,000 R. P. M. to 500 R. P. M. may, of course, be varied by using different gear ratios. The point is that it is impractical to use a direct drive for motor-actuated pencil sharpeners, for either the motor must be too large for a practical pencil sharpener, or the device will stall unless handled in the most careful manner, something not to be expected from a casual user.

The shaft 68 of the cutter mechanism 25 rotates, as has been stated, substantially 500 R. P. M. The cutter cylinders 80 rotate with the shaft 68, but they also rotate independently about their own axes through the contact of the pinions 81 with the ring gear 75. The aprons 85 and 87 shunt substantially all of the shavings and other material over the ring gear 75 and pinions 81 into the space below the cutter mechanism 25. However, the groove 76 permits any shavings and other material, which may work into the ring gear track to fall into the space below the cutter mechanism 25, and thence into the drawer 28.

The switch mechanism 27 is very effective in the automatic actuation of the motor 24. It is of light construction and of free pivotal movement. It is balanced, so that the casing 111 normally assumes the position shown in Fig. 7. It requires but the slightest force on the part of a pencil inserted through the opening 50 against the face 106 to pivot the switch mechanism 27 75

to dispose the casing 111 in the position shown in Fig. 8, which is the closed circuit position.

The drawer 28 fits snugly into the space provided and receives shavings, and the like, from the cutting mechanism 25. In the particular configuration disclosed, the front of the drawer 28 blends into the front of the cover 22, as is readily appreciated from an inspection of Figs. 1 and 2.

The barrel of the cutting mechanism 25 is disposed at substantially 45° to approximate the angle at which a pencil is normally held in writing. The angular disposition of the barrel, defined, of course, by the position of the cutter shaft 58, permits one sharpening a pencil to insert it with facility. In other words, the present sharpener 20 simplifies to a minimum the sharpening approach in anticipating the normal manner in which a pencil is held by one proceeding to sharpen the same.

Manifestly, there are possible changes in the construction and arrangement which are within the confines of the present inventive concept. The motor 24 may be of any suitable high-speed type. The gearing 26 may be varied as to ratio to reduce the effective speed of the motor 24 as desired for a particular sharpener construction. The switch mechanism 27 may be of the contact type, a construction which would be preferable where the sharpener was subjected to a considerable amount of movement, as upon a train or ocean liner, for it is possible that upon these carriers the inevitable agitation transmitted to the sharpener would occasionally close the motor circuit through an abrupt movement of the mercury 113 into momentary contact with the wires 112. Manifestly, suitable materials and suitable configurations are to be employed for the elements of the sharpener 20.

It is apparent, therefore, that there has been provided a power-actuated pencil sharpener which fulfills all of the objects and advantages sought therefor.

It is to be understood that the foregoing description and accompanying drawings have been given by way of illustration and example, and not for purposes of limitation, the invention being limited only by the claims which follow.

What is claimed is:

1. A pencil sharpener comprising a support, a casing, rotary cutting means mounted on said support, and means for driving said cutting means, said rotary cutting means including spaced cutting rollers, each having an associated pinion, a ring gear with which said pinions co-operate, and a pair of aprons overhanging the ring gear formed as part of the cutter shaft disposed to prevent the passage of shavings and other material from the cutters to the ring track.

2. A pencil sharpener comprising a support, a casing, rotary cutting means mounted on said support, and means for driving said cutting means, said rotary cutting means including spaced cutting rollers, each having an associated pinion, a ring gear with which said pinions co-operate, means for substantially preventing the passage of shavings and other material into the ring track from the cutters, and means for discharging any shavings or other material from the ring track which may sift thereinto.

3. A pencil sharpener comprising a support, a casing, rotary cutting means mounted on said support, and means for driving said cutting means, said rotary cutting means including spaced cutting rollers, each having an associated

pinion, a ring gear with which said pinions co-operate, a pair of aprons formed as part of the cutter shaft disposed to prevent the passage of shavings and other material from the cutters to the ring track, and a groove in the member of which the ring gear forms a part leading from the lower part of the ring track into the space below the cutters to drop material which has sifted into the ring track.

4. A pencil sharpener comprising a support, rotary cutting means mounted on said support, and means for driving said cutting means, said rotary cutting means including pinions by which said driving means rotates said rotary cutting means, a ring gear with which said pinions co-operate, and a pair of aprons overhanging the ring gear disposed to prevent the passage of shavings and other materials from the cutting means to the ring track.

5. A pencil sharpener comprising a support, 10

5 rotary cutting means mounted on said support, and means for driving said cutting means, said rotary cutting means including spaced cutting rollers, each having an associated pinion, a ring gear with which said pinions cooperate, and means for discharging any shavings or other material from the ring track which may sift thereinto.

6. A pencil sharpener comprising a support, 10
15 rotary cutting means mounted on said support, and means for driving said cutting means, said rotary cutting means including spaced cutting rollers, each having an associated pinion, a ring gear with which said pinions cooperate, and a groove in the member of which the ring gear forms a part leading from the lower part of the ring track into the space below the cutters to drop material which has sifted into the ring track.

EDWARD C. HOFFMANN.
